DESIGN FOR A KNIFE

Gerald N. Coughlan, East Orange, N. J.

Application November 7, 1935, Serial No. 59,424

Term of patent 7 years

To all whom it may concern:

Be it known that I, Gerald N. Coughlan, a citizen of the Irish Free State, and a resident of East Orange, county of Essex, and State of New Jersey, have invented a new, original, and ornamental Design for a Knife, of which the following is a specification, reference being had to the accompanying drawing forming a part thereof.

I claim:

The ornamental design for a knife as shown.

GERALD N. COUGHLAN.
